(57) **CLAIM**

The ornamental design for a mobile phone, as shown and described.

DESCRIPTION

FIG. 1 is a perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof where the bottom plan view is a mirror image;

FIG. 7 is a rear perspective view thereof;

FIG. 8 is a reference view thereof showing an example of the usage of the subject design;

FIG. 9 is a perspective view in a condition that the mobile phone is folded in half;

FIG. 10 is a front view of FIG. 9;

FIG. 11 is a rear view of FIG. 9;

FIG. 12 is a left side view of FIG. 9;

FIG. 13 is a right side view of FIG. 9; and,

FIG. 14 is a top plan view of FIG. 9 where the bottom plan view is a mirror image.

The short dashed lines along the rear of the mobile phone illustrate a stitching pattern that forms part of the claimed design; the dot-dot-dashed lines showing a hand in FIG. 8 are environmental subject matter only and form no part of the claimed design.
